POWER CIRCUIT FOR ELECTRIC RANGES

Douglas David Findlay, Carleton Place,
Ontario, CanadaApplication November 19, 1934,
Serial No. 753,559 1/2

3 Claims. (Cl. 219—20)

This invention relates to oven heat control for electric ranges and more particularly to the electric circuits for controlling the flow of current to the heating elements.

5 In ovens of this character it is common practice to provide two heating elements, a top element and a bottom element, sometimes with a switch controlling the power supply to both elements and a single-pole thermostatically controlled circuit breaker in the baking element circuit, but more generally with two switches, one for each heating element and a double-pole thermostatically controlled circuit breaker which 10 interrupts the power supply to each switch. The latter arrangement is cumbersome and expensive while the former is only partially automatic. Sometimes, in order to control both oven elements with a single pole circuit breaker, both elements are fed from the same controlled leg of the 15 3-wire supply in parallel. This arrangement causes an undesirable voltage drop, resulting in slower action in the preheating position, and creates an unbalanced load, which is objectionable. A pilot light is sometimes provided to indicate when the elements are energized. Such 20 circuit arrangements have not provided for most efficient and rapid preheating of the oven, nor do they provide for single manual control of the power load circuit whereby both heating elements 25 may be connected in series with high voltage current supply or either element separately with low voltage current supply.

An object of the present invention is to provide 30 an improved circuit including a single-pole thermostatic circuit breaker and pilot light with unitary manual control, so that both heating elements may be heated in series at high voltage and either of the elements may be heated separately at low voltage. A further object is to 35 provide a circuit arrangement in which a relatively inexpensive single-pole thermostatic circuit breaker and pilot light are incorporated in all of a plurality of the oven heating circuits controlled by a manually operated switch, and in 40 which the lower voltage power supply is provided for each heating element through the leg of the power supply circuit which contains the thermostatic circuit breaker. Another object is to provide an improved dial arrangement for setting 45 the temperature at which the thermostatic circuit breaker automatically breaks the power supply circuit feeding the heating elements.

The invention will now be described with reference to the accompanying drawing, in which 50 Figure 1 represents the electric circuit;

Figure 2 is a front view of an electric range, partially broken away;

Figure 3 represents the three different connections of the heating elements in the circuit; and

Figure 4 illustrates an arrangement of the dial 5 of the thermostatic control on the panel.

In the drawing, 1 represents the top and 2 the bottom heating element for the oven illustrated in Figure 2. 3 is a multi-way switch, operable from the switch panel 4; 5 a single-pole thermostatically controlled circuit breaker, of well known construction, having a control dial 6 on the switch panel, and 7 represents fused cutouts for the power supply which is connected to the terminal block 8 for reception of 220 volt current 10 or 110 volt current, depending upon the position 15 of the switch 3. A pilot light 9 is connected with the circuit breaker 5 and the common line terminal 13.

The heating elements 1 and 2 are connected 20 in series and to the switch 3 with wires 10 and 11, while a common wire 12 also contacts with the switch at a point 13. The power line 14 connects one fused cutout with the switch, while the other power line 15 passes through the circuit breaker 5 to the switch and the neutral line 16 leads directly from the terminal block to the switch.

The dial for setting the temperature at which the thermostatic circuit breaker operates to interrupt the current flow is arranged in an opening in the panel 6, as illustrated more or less diagrammatically in Figures 2 and 4. The dial may take the form of an open-ended cylinder 17 mounted for rotation on a shaft 18 and having a 30 transparent wall 19 carrying a desired temperature scale. An index pointer 20 is provided on the outturned lip of the panel opening. The dial may be provided with knurls 21 to afford gripping contact for rotating the dial. The pilot 35 light 9 is located within the cylinder to illuminate the temperature scale and, at the same time, indicate if the power is on or off. Alternatively, if desired, the pilot lamp may be arranged behind a window in the panel in a known manner. 40

The three operating positions of the circuit with respect to the two heating elements, as controlled by the switch, are diagrammatically illustrated in Figure 3. In the preheating or "1" position, when it is desired to raise the temperature of the oven quickly, both elements are energized in series by the 220 volt current supply of the two power lines 14 and 15, the neutral wire being broken as indicated at "X". With the switch in the "2" position "Bake" or "3" position 50 55

"Broil", the same power circuit energizes the heating element 1 or 2 as required with 110 volt current supply of one power line 15 and utilization of the neutral wire 16, the other power line 5 14 being broken as indicated at "X" in each case. The thermostat control and pilot light are, as shown, in the energized circuit in all positions.

The operating positions of the circuit may be described with respect to Figure 1 as follows:

10 (1) line 15 through switch to wire 10, element 1, element 2, wire 11 through switch to line 14; (2) line 15 through switch to wire 11, element 2, wire 12 through switch to neutral line 16; (3) line 15 through switch to wire 10, element 1, wire 15 12 through switch to neutral line 16. The utilization of power line 15 in all operating positions permits control of the circuit at all times by means of the single-pole circuit breaker 5 in the line 15. The pilot light 9 by connection to the 20 circuit breaker and to wire 12 at terminal 13 of the switch is also in the energized circuit at all times.

It will be observed that this circuit arrangement affords simplicity of operation by a single 25 manual switch control of all heating positions of the elements, while in all such positions the circuit is automatically controlled by the single-pole thermostatic circuit breaker, with the pilot light burning when the power is on. With the 30 switch in No. 1 position, the two heating elements are connected in series across the high voltage line, giving maximum heating effect in the oven, while in positions No. 2 and No. 3 of the switch the baking and broiling circuits, respectively, 35 are energized. The pilot light is always in circuit with the automatic control and thus when the automatic control breaks the circuit the light goes out, indicating that the desired oven temperature has been reached. This automatically 40 indicates the time at which the switch 3 should be manually shifted. It will be appreciated that this arrangement greatly facilitates minimum power consumption as well as maintenance of best temperature conditions in the oven.

45 With this circuit arrangement a single-pole, relatively inexpensive circuit breaker adequately provides for thermostatically breaking whichever power circuit may be in operation. The switch 3 may be of any desired construction to operate as 50 shown.

If desired, the pilot light may be arranged to come on when the temperature, for which the

thermostatic circuit breaker is set, has been reached. In this case the pilot light is connected across the binding posts of the circuit breaker 5.

A clock may be inserted in the power load circuit between the circuit breaker and the terminal block to close and break the circuit automatically at fixed times.

The circuit is adapted for any desired power voltages and the higher voltage may be double the lower voltage or the square root of three times 10 the lower voltage, as is sometimes the case.

I claim:

1. An electric circuit for the oven of cooking ranges comprising two heating elements, a power supply circuit for said elements including two 15 energized wires and a neutral wire, and control means for said circuit comprising a switch, said energized wires and the neutral wire being connected to terminals in the switch, connecting wires leading from terminals in the switch to 20 each of said elements and a third common wire leading from a terminal in the switch and connected to both of said elements, the switch in one operating position being arranged to connect the terminals of said energized wires to the terminals of said connecting wires with the terminals of the neutral wire and the common wire disconnected, and in other operating positions to connect the terminal of the same one of the energized wires to either of the terminals of the 30 connecting wires and the terminal of the neutral wire with the terminal of said common wire, whereby one of said energized wires is commonly utilized in all operating positions of said circuit.

2. A circuit as defined in claim 1 wherein a 35 single-pole thermostatically controlled circuit breaker is interposed in said commonly utilized wire and arranged to open and close said circuit when the temperature in the oven reaches predetermined limits.

3. A circuit as defined in claim 1 wherein a single-pole thermostatically controlled circuit breaker is interposed in said commonly utilized wire and arranged to open and close said circuit when the temperature in the oven reaches 45 predetermined limits, and wherein a pilot light is connected between the circuit breaker and said common wire terminal of said switch whereby said pilot light is energized in all operating positions of said circuit.
